UNITED STATES PATENT OFFICE

WEGOR E. MATHISON, OF CHICAGO, ILLINOIS

ATTACHMENT FOR SMOKERS' PIPES

Application filed July 18, 1927. Serial No. 206,467.

This invention relates to improvements in attachment for smoker's pipe, and one of the objects of the same is to provide an improved attachment adapted to be applied to the pipe and by means of which the pipe may be readily cleaned, the said attachment being adapted to remain attached to the pipe and at the same time will not interfere with the use of the pipe.

10 A further object is to provide an improved attachment of this character which will be compact and which will not present an unsightly appearance to the pipe, and at the same time may be readily removed if desired.

15 To the attainment of these ends and the accomplishment of other new and useful objects as will appear, the invention consists in the features of novelty in substantially the construction, combination and arrangement 20 of the several parts hereinafter more fully described and claimed and shown in the accompanying drawing illustrating this invention, and in which

Figure 1 is a perspective view of a smoker's 25 pipe, having a cleaning attachment applied thereto constructed in accordance with the principles of this invention.

Figure 2 is a vertical, sectional view of the pipe bowl and of the cleaning attachment.

30 Figure 3 is a top plan view of Figure 1, with parts broken away.

Figure 4 is a perspective view of the attachment shown in Figure 2.

35 Figure 5 is a view in side elevation, partly in section and partly broken away, of a modified form of the invention.

40 Referring more particularly to the drawing the numeral 10 designates the bowl of a smoker's pipe to which the stem 11 is attached in the ordinary and usual manner.

45 The attachment consists essentially of a body portion 12 constructed of any suitable material, one end of which is bent or curved forwardly as at 13 and is provided with a depending portion 14. The depending portion 14 is adapted to enter a counter-bored portion 15 of the aperture 16 in the bottom of the bowl of the pipe, and the portion 14 of the cleaner is provided with an opening 17 there- 50 through which is of substantially the same

diameter as and registers with the opening 16 extending through the bottom of the bowl, and which opening has communication with a passage 18 in the stem 11. The portion 14 fits snugly within the aperture 15 so that the 55 forwardly bent portion 13 will rest upon the bottom of the bowl, the body portion of the cleaning device extending upwardly along the side of the bowl. The upper extremity of the body portion 12 is deflected laterally as at 60 19 so as to project over the top edge of the bowl and to form a handle. Connected with the handle 19 is a depending portion 20 having a flange 21 which extends on both sides of the depending portion 20 and is arranged 65 substantially parallel with the handle portion 19. The forward edge 22 of the flange 21 terminates short of the adjacent portion of the body 12 and is adapted to enter a circumferential groove 23 opening through the periphery of the bowl 10 adjacent the top thereof.

70 The rear portion of the flange 21 cooperates with the handle portion 19 and serves as a means whereby the device may be rotated within the pipe bowl.

75 The body portion 12 is of any desired width and the longitudinal edges thereof are beveled as at 24 to form cutting edges.

When the attachment is connected to the pipe the portion 14 is inserted in the counter-bore 15 and the handle 19 projects over the top of the pipe, while the flange 22 is inserted into the groove 23. This flange may be so inserted by bending or springing the upper portion of the cleaning device.

80 When the flange 22 is seated in the groove 23 and the portion 24 is in the counter-bore 15 the body portion 12 may be rotated within the pipe bowl by the fingers of the hand engaging the handle portion 19.

85 The opening 17 being of the same diameter as the opening 16, it will be manifest it will not interfere with the smoking of the pipe, nor will it interfere with the insertion of any cleaning device from either the inside 90 of the bowl or through the bottom of the bowl when the stem 11 is removed.

95 In the form of the invention shown in Figure 5, a member 25 is provided which is pivotally connected as at 26 with a depend- 100

ing portion 27 of the handle 19. The forward edge 28 of the portion 25 is adapted to project into the groove 23. A spring 29 may be provided intermediate the portions 19 and 25, and this spring 29 tends normally to hold the edge 28 of the member 25 seated within the groove 23. With this form of the invention it will be manifest that the cleaning device may be readily removed when desired by swinging the member 25 about its pivot 26, while in the form of the invention shown in Figures 1 to 4, the device may be removed, if desired, by springing the upper portion of the cleaner in such a manner that the forward edge 22 will pass out of the groove 23.

While the preferred forms of the invention have been herein shown and described, it is to be understood that various changes may be made in the details of construction and in the combination and arrangement of the several parts, within the scope of the claims, without departing from the spirit of this invention.

What is claimed as new is:—

25 1. In combination, a pipe bowl having a smoke passage in its bottom, the walls of said passage being imperforate, a cleaning device, said device embodying a body portion, a projection on said body adapted to be loosely and removably seated in a portion of said passage and disposed entirely within the pipe, the body of said device extending along the wall of the bowl towards and terminating adjacent the top of the bowl, said body being rotatable within the bowl, the said projection constituting a pivot.

2. In combination, a pipe bowl having an opening in the bottom thereof, a cleaning device, said device embodying a body portion, a projection on said body adapted to be seated in said opening, the body of said device extending along the wall of the bowl towards and terminating adjacent the top of the bowl, said body being rotatable within the bowl, the said projection constituting a pivot, there being an opening through the body of the cleaner communicating with an opening in the wall of the pipe bowl.

3. In combination, a pipe bowl having a smoke passage in its bottom, the walls of said passage being imperforate, a cleaning device, said device embodying a body portion, a projection on said body adapted to be removably seated in a portion of said passage and disposed entirely within the pipe, the body of said device extending along the wall of the bowl towards and terminating adjacent the top of the bowl, and means at the top of the bowl for rotation about the bowl and for maintaining said projection seated in said opening, said projection constituting a pivot.

4. A cleaning attachment for smokers' pipe bowls, said attachment embodying a body

portion within and extending along the wall of the bowl in a direction from the top to the bottom thereof, means for rotatably securing the lower end of said body portion to the bottom of the bowl, and means for securing the top of the said body to the top of the bowl for rotation therearound, there being an opening through the said body portion adjacent the bottom of the bowl.

5. A cleaning attachment for smokers' pipe bowls, said attachment embodying a body portion within and extending along the wall of the bowl in a direction from the top to the bottom thereof, means rotatably and detachably securing the lower end of said body portion to the bottom of the bowl, the last said means being disposed entirely within and concealed from the outside of the said bowl, and means for securing the top of the said body to the top of the bowl for rotation therearound, one of the edges of said body portion being beveled to form a cutting edge.

In testimony whereof I have signed my name to this specification on this 14th day of July, A. D. 1927.

WEGOR E. MATHISON.
